US00D949899S

(12) **United States Design Patent** (10) **Patent No.:** **US D949,899 S**
Olson (45) **Date of Patent:** **** Apr. 26, 2022**

(54) **DISPLAY SCREEN OR PORTION THEREOF WITH GRAPHICAL USER INTERFACE**

(71) Applicant: **Starlight AG, LLC**, Minneapolis, MN (US)

(72) Inventor: **Virginia C. Olson**, Minneapolis, MN (US)

(73) Assignee: **STARLIGHT AG, LLC**, Minneapolis, MN (US)

(**) Term: **15 Years**

(21) Appl. No.: **29/754,105**

(22) Filed: **Oct. 6, 2020**

Related U.S. Application Data

(63) Continuation of application No. 29/670,251, filed on Nov. 14, 2018, now Pat. No. Des. 898,058.

(57) **CLAIM**

I claim the ornamental design for a display screen or portion thereof with graphical user interface, as shown and described.

DESCRIPTION

The FIGURE is a front view of a display screen or portion thereof with graphical user interface, showing the new design.

The outermost broken line illustrates a display screen and forms no part of the claimed design. The remaining broken lines illustrate portions of a graphical user interface and form no part of the claimed design.

1 Claim, 1 Drawing Sheet
